BREAD BOX

Jack Solomon, Island Park, N.Y., assignor to Lincoln Metal Products Corporation, Brooklyn, N.Y.

Filed Aug. 7, 1970, Ser. No. 24,366

Term of patent 14 years

Int. Cl. D7—99

U.S. Cl. D44—6

FIG. 1 is a perspective view of a bread box showing my new design;

FIG. 2 is a top plan view thereof, on an enlarged scale;

FIG. 3 is a side elevational view thereof, on an enlarged scale; and

FIG. 4 is a front elevational view thereof, on a yet more enlarged scale.

I claim:

The ornamental design for a bread box, substantially as shown.
